UNITED STATES PATENT OFFICE.

GEORGE L. THOMAS, OF BROOKLYN, NEW YORK, AND EDWARD C. SEWARD, OF MONTCLAIR, NEW JERSEY; SAID SEWARD ASSIGNOR TO SAID THOMAS.

RAILROAD SIGNAL SYSTEM.

SPECIFICATION forming part of Letters Patent No. 508,356, dated November 7, 1893.

Application filed July 1, 1893. Serial No. 479,342. (No model.)

To all whom it may concern:

Be it known that we, GEORGE L. THOMAS, of Brooklyn, in the county of Kings and State of New York, and EDWARD C. SEWARD, of Mont-
clair, in the county of Essex and State of New Jersey, have invented a new and useful Improvement in Railroad Signal Systems, of which the following is a specification.

Our invention relates to an improvement in railroad signal systems in which a set of signals is under the control of a passing train to indicate to another train going either in the same direction or in the opposite direction, its location with respect to certain pre-determined blocks or subdivisions into which the track may have been subdivided.

Our present invention is more particularly directed to the introduction of header signals for use particularly on single track rail-
ways, into the system of rear signals shown and described in our United States Letters Patent No. 500,829, granted July 4, 1893, in connection with certain modifications of that system or parts thereof in respect to the form and arrangement of the signals proper and their actuating mechanism.

A practical embodiment of our invention is represented in the accompanying drawings in which—

Figure 1 is a view of a signal post, a set of signals and their operating mechanism, the post being shown in vertical longitudinal section and the view being taken in a direction transverse to the track. Figs. 2, 3 and 4 indicate upon a smaller scale the three positions which the signal arms assume to indicate danger, caution and safety. Fig. 5 is a view, looking in the direction of the track, of the mechanism represented in Fig. 1 the signal post being shown in section to disclose the operative parts therein. Fig. 6 is a view looking transversely across the track of one of the special signal posts to be located at the opposite ends of a shunt track, the post being shown in section to disclose the operative parts therein. Fig. 7 is a partial view of the same, looking in the direction of the track. Fig. 8 is a view in detail, showing the header signal supporting bracket partially broken away to show the contact piece on the header and signal arm. Fig. 9 is a partial edge view

of one of the header signal arms and the electric connections at its point of support. Fig. 10 is a diagrammatical view, representing in plan a portion of a track including three successive signal posts and showing the electrical connections between the signal mechanism and the contact posts at the sides of the track; and Fig. 11 is a similar view, showing the connections at the point where a shunt track is located.

The signal post is denoted in Figs. 1 and 5 by A and in Figs. 6 and 7 by A', the latter being substantially a double post or a post sufficient to accommodate a double set of signaling mechanism. The posts are made hollow with hollow enlarged heads for receiving the signal operating mechanism. The signals proper which we find it desirable to employ are those denoting danger, caution and safety. We construct them preferably as shown clearly in Figs. 2, 3 and 4 in which an arm B colored red and provided with a red lens is fixed to rotate together with an arm B' colored green and provided with a green lens, the two arms being set preferably at an angle of one hundred and twenty degrees and not only being different in color but also differently shaped, the red arm commonly being provided with a swallow tail end b, while the green arm is provided with a blunt end having V-shaped projections b' projecting in opposite directions from its edges. The arms B and B' are provided with a counterbalance arm B² which may be colored white and fixed to move with the arms B and B' and radiating from them at an angle of about one hundred and twenty degrees. The signal arms counterbalance is fixed to rotate with a spindle C suitably mounted in the enlarged head of the signal post, the signal arms being located exterior to the head of the signal post and in position to be thrown past the face of the post as the spindle C turns, so as to be plainly observed in either direction along the track. When the arms are thrown into the position shown in Fig. 2 with the red extending horizontally and green diagonally upward the position indicates danger. When thrown into the position shown in Fig. 3 with the green horizontal and the red diagonally downward the signal indicates caution and when

thrown into the position shown in Fig. 4 with the green extending diagonally downward and the red diagonally upward the position indicates safety. This position will also bring the counterbalance B^2 into a general horizontal direction and if colored white will indicate safety, although the position of the red and green arms is sufficient to clearly indicate safety. It will thus be seen that not only is there the color to guide and attract the engineer but there is also the different shape of the arm on which the color is placed and in addition to this the different relative positions of three arms as a second precaution.

15 The spindle C is permitted to rotate at intervals to throw the several signals into position by means of three independent electro magnets C C' C² having stops upon their armatures to engage abutments on disks C³ C⁴ C⁵ respectively in the manner quite similar to that shown and described in our former patent herein above referred to, and need not be repeated at length herein. The spindle C is constantly under pressure to rotate it in one direction, such pressure being in this present case applied by means of a weight D suspended by a cord or chain d which extends from the weight up and over a guide pulley d', thence down to a winding drum d² having 30 fixed to rotate therewith a sprocket wheel d³ connected by a sprocket chain d⁴ with a sprocket wheel d⁶ fixed on the spindle C. The weight D may be wound up by hand at regular intervals by means of any well known or 35 approved winding mechanism.

35 In connection with the mechanism for setting the signals at the rear to indicate danger, caution and safety, according as the train has just passed onto the block, cleared the first 40 half of the block, or passed off the block, as fully shown and described in our patent hereinabove referred to, we provide signals which we call header signals, two in connection with each ordinary signal post and set of rear signals, one to signal the approach of a train 45 running on a single track in one direction and the other to signal the approach of a train running on the same track in the opposite direction. These header signals are denoted 50 by E and E'. They are pivotally secured near their lower ends side by side between the arms of a bracket a extending toward the track from the post A at a point below the rear signals and when not in use to indicate 55 the approach of a train are held upright along the face of the signal post A. At their lower ends below their pivotal point the signals E, E' are provided with extensions e, e', preferably curved, as shown, and adapted to enter, 60 as the signal arm falls, through a slot a' in the post one upon each side of the sprocket chain d⁴ which actuates the spindle carrying the rear signals. The sprocket chain d⁴ is provided at suitable intervals with cross pins d⁵ which, when the signal arms E and E' are 65 down in signaling position, will engage the extended ends e, e' of the signal arms and as

the chain moves to rotate the rear signals will engage the extended ends e, e' of the header signals and throw them into the upright position indicated in full lines in Fig. 5. The signal E when in its dropped position is intended to occupy a position about at right angles to the post A, as shown in the fine dotted lines in Fig. 5, while the signal arm E' 70 when in its dropped position is intended to occupy the oblique position, as shown in the coarser dotted lines in Fig. 5. The signal arms E and E' may be conveniently arrested in their dropped positions, the former by the 75 upper wall of the slot a' and the latter by a pin or abutment a² extending from the side wall of the slot across the path of its extended end e'.

Each of the arms E, E' is held in upright 80 position by means of a spring actuated latch e² attached to its edge toward the post as shown in Fig. 5 and adapted to interlock with the hooked end f of a vibrating arm F pivotally secured to a suitable support within the 85 head of the post A, the opposite arm or end f' of the said vibrating arm being provided with a slight depression f² for the reception of the upper end g of a vibrating lever G pivotally secured to a suitable support within the 90 head of the casing and carrying upon its opposite arm g' the armature g² of an electro magnet g³. The lever G also has fixed thereto 95 so as to vibrate therewith an anchor escapement H, the teeth h and h' on the opposite 100 ends of the escapement being adapted to alternately engage radially extended teeth h² on a disk h³ actuated by a weight h⁴ tending to turn it at all times in one direction, in the 105 present instance over toward the right. The 110 teeth h² are located at regular intervals along the periphery of the disk h³ in the present instance one-sixth of the periphery apart.

A similar mechanism to that just described with respect to the operation of the 115 header arm E is provided for the header arm E'.

Fixed upon the spindle C intermediate of the escapements, toothed disks, and electro magnets which operate the header arms E, E'; is a disk I provided at intervals on its periphery with projecting blunt faced teeth i, i' and with an ordinary ratchet tooth i² arranged at intervals of one-third of the periphery apart, the blunt faced teeth i and i' 120 being located in different planes transverse to the spindle C and provided on their blunt faces with sunk gear teeth i³. The teeth i, i' and i² on the periphery of the disk I are adapted, as the spindle C together with the 125 disk I is rotated, to engage abutments in the present instance pins h⁵ projecting from the adjacent faces of the disks h³ and thereby rock the disk h³ step by step over toward the left in the direction to wind up the weight 130 h⁴. The pins h⁵ correspond to the teeth h² at the periphery of the disk with the exception that the pins h⁵ are omitted throughout a portion of the disk in the present instance

two of them being omitted so that when the disk h^3 has been turned to the left a predetermined distance, the teeth on the disk I will work idly past the said pins h^5 and will not further rotate the disk h^3 .

5 The gear teeth on the face of the teeth i on the disks E are adapted to engage a toothed wheel k fixed to rotate with the arm k' of a swinging spectacle K, while gear teeth on the 10 face of the tooth i' are adapted to engage a similar toothed wheel fixed to rotate with the arm of the second spectacle K' pivoted in axial alignment with the spectacle K and by the side of it. In the present instance the 15 spectacle K is assumed to be red and the spectacle K' green.

In operation, suppose a train to have passed the signal post represented in Figs. 1 and 5 and to have thereby set the signal to danger. 20 By a suitable electric connection to be hereinafter referred to by means of the diagram Fig. 10, the train will energize the electro magnet g^3 or its companion at the second signal post beyond and will thereby swing the 25 lever G of that signal into the position shown in dotted lines in Fig. 5, releasing the vibrating arm F which by means of its weighted arm f' will vibrate sufficiently to release its hooked end f from the latch e^2 and thereby 30 permit the arm E or its companion E' to drop into position to signify to a train coming in the opposite direction that this train is already occupying the second block from it. 35 The arms E and E' are supported eccentrically so that they will readily fall when released. As the arm E or its companion E' drops, a pin e^3 projecting from its edge toward the post will be withdrawn from a gravity stop e^4 permitting the latter to swing down 40 into engagement with the hooked end f of the vibrating arm F and cause the latter to resume its horizontal holding position so as to permit the end g of the vibrating lever G to be again rocked into position beneath the 45 arm f' . In like manner as the train advances along the track it will set the header signals one after another at the second post ahead. As the train reaches the signal post where it has previously set a header signal and provided 50 no train in advance of it has previously passed that post after the said train had set it, in setting the rear signal to indicate danger, the sprocket chain d^4 with the pins d^5 thereon will be advanced and by engagement 55 with the cross pins thereon with the projecting end or ends of the header signal or signals as the case may be, it will return the header signal to its upright position by the springing of the latch e^2 under the hooked 60 end f' of the vibrating arm F, where it will be retained, the pin e^3 at the same time throwing the gravity stop e^4 out of the way. As the rear signal is thrown successively to danger or to caution, the gear on the teeth i, i' will engage the spur wheels in connection with the 65 spectacles K and K' and throw the red spectacle up into position to show the red signal

when the red arm is out to danger and the green spectacle K' up into position to show the green signal when the green arm is out 70 to denote caution. The spectacles will fall one after another of their own weight as soon as the signal changes.

In order to provide for the passage of several trains past a given signal post, each operating the vibrating lever G at the second signal post ahead and at the same time preventing the setting of a rear white or safety signal by the trains which shall subsequently pass that second signal post ahead, until the last train shall have reached it and passed it; we provide the escapement mechanism herein above described and connect it with the electric circuit which changes the rear signal to white in the following manner: On the side 85 of the disk h^3 there is a contact plate h^6 which, when the disk h^3 is turned into the position shown in Fig. 5 forms a closed circuit between the separated contact points h^7 and h^8 which form the termini of a break in the safety signal circuit and said contact plate h^6 is also sufficiently long so that when the disk h^3 shall have been rocked the distance between two teeth h^2 by the swinging of the lever G and the consequent operation of the escapement H, 95 these two contact points h^7 and h^8 will still be in engagement with the contact plate h^6 and the circuit will remain complete so that this train as it passes from a block will effect the setting of the safety signal at the beginning of that 100 block. If, however, more than one train shall have passed onto the block, the action of the escapement will have advanced the disk h^3 two or more steps and will thereby have moved the contact plate h^6 such a distance as to 105 break circuit between the contact points h^7 and h^8 and thereby shut off the possibility of setting a rear signal to safety until the last train shall have passed off the block. As the trains successively pass a post where the disk 110 h^3 has been permitted to rock two or more steps to the right, in operating the rear signals for that post, each train will by the rotation of the disk I one-third of a revolution have returned the disk h^3 one step to the left 115 by the engagement of one of the teeth i, i' or i^2 with one of the pins h^5 until when the last train reaches that post it will find the safety signal circuit complete and will rock the disk h^3 back to its normal position, shown in Fig. 120 5 at the same time that it sets the safety signal at the beginning of that block.

The signal mechanism at the opposite ends of the shunt or switch track is somewhat modified in detail in order to provide for the return of the header signal to its upright position as the train passes from the main onto the shunt track so that the train coming in the opposite direction may find the line clear, or dropping the header signal again when the 130 train from the shunt track returned onto the main track to continue its course.

The rear signal mechanism is duplicated in a manner quite similar to that in which the

signaling mechanism in our patent hereinabove referred to is duplicated for shunt purposes while the header signals in connection with our present special shunt signaling mechanism are not duplicated but the header signal for one direction is made to co-operate with the one set of rear signaling mechanism while the header signal for the opposite direction is made to co-operate with the other rear signaling mechanism. This special signaling mechanism within the post A comprises in the present instance as in the former a duplicate of the rear signaling mechanism, shown as set up within the post A herein before referred to, one of the disks h^3 with its escapement H for operating the header signal E being mounted in position to be engaged by a disk I' fixed to rotate with one set of rear signals and the companion disk h^9 with its escapement H' for operating the header signal E' being engaged by a disk I² fixed to rotate with the other set of rear signals. In the present instance I have shown the spindle C' fixed and the several parts which rotate therewith attached to sleeves C² and C³ mounted on the fixed spindle C'. In order to return either of the header signals in this special signal station to safety independently of the movement of the rear signals, we have provided a second sprocket chain L and L', one for each set of signals in this special arrangement which pass over sprocket wheels l and l' respectively loosely mounted on sleeves C² and C³ and thence around the sprocket wheels l² and l³ at or near the base of the signal post which latter sprocket wheels are fixed to rotate with winding drums caused to rotate by weights M, M' connected therewith by means of cords or chains m and m' leading from the weights over guide pulleys and thence down to the drums. The sprocket chains L and L' are intended to travel along side of the sprocket chains d⁴ of the rear signaling mechanism and have projecting therefrom pins l⁴ corresponding in position to the pins d⁵ on the chains d⁴ so that when either of the chains L or L' are permitted to advance the pins l⁴ thereon will return either or both of the header signal arms which may be down to their upright positions independently of the movement of the chains d⁴. A disk l⁵ with abutments on its face is fixed to rotate with the sprocket wheel l and a corresponding disk l⁶ is fixed to rotate with the sprocket wheel l' and also provided with abutments on its face. The disks l⁵ and l⁶ are controlled by means of stops n and n' on the armatures of electro magnets N and N' and every time either of the electro magnets N or N' is energized the disk l⁵ or l⁶ is permitted to rotate a distance sufficient to advance the chain L or L' the distance between two consecutive pins l⁴. The electro magnets N and N' are in circuit with contact plates alongside the shunt tracks as will hereinafter appear when reference is made to the diagrams.

In order to release either of the header arms E or E' independently of the ordinary means of releasing them, we provide the hooked ends of the vibrating arms F with joints so that the hooked portions O (see Fig. 7) may be lifted independently of the movement of the arm as a whole, the joint o being such as to permit the hooked end O to lift freely but not to swing below the alignment with the rest of the lever. We employ for this a joint of well known or approved form such as in common use for example in connection with carriage braces. Independent electro magnets P and P' are located in position when energized to attract their armatures p and p' fixed to the ends O of the arms to lift the one or the other of the ends O to set free one or the other of the header arms independently of the arm F as a whole. The electro magnets P and P' are in circuit with contact plates alongside of the shunt track, as will hereinafter appear from the diagrams.

A single line connection and contact plate is made to answer the purpose of raising the header arm to its upright position when down and to lower it when up as the train goes on to or passes off from the shunt track by connecting one pole of each of the magnets N and P with the line wire (see Fig. 7) and connecting their opposite poles independently with contact pieces n² and p² fixed in the wall of the supporting bracket a in position to engage a contact piece Q in the side of the arm E according as the arm is dropped or upright, the contact piece Q having a ground connection q.

The diagram Fig. 10 shows a series of ordinary stations or posts A with their rear signal connections and contact plates all as shown and described in our patent referred to and with the additional connections and contact plates for operating the headers. Beginning with the station A at the left of the sheet and supposing the train to be running from left to right and the signal at that station at the left to be at white for safety; the contact plate R is that which connects with the previous signal at the left to set it to white as the train passes the post A. The contact plates R', R² and R³ which are next engaged by the passing train in the order named, leave the signal at the post A at the left set to red or danger in the following manner: The signal is held at white by the stop of the magnet c in engagement with the disk c³ (see Fig. 1) and the magnet c is in circuit with the plate R³ at the side of the track, so that as the train makes contact with the plates R' and R², and thereby energizes successively the magnets c² and c', it will have no effect upon the signal as the stops of those magnets do not at this moment hold the signal. The contact however with the plate R³ will permit the signal to turn from its position of safety into its position of danger (represented in Figs. 2 and 5) and it will be arrested in that position by means of the stop under the

control of the magnet c' . The words "To red," "To green," "To white" as they appear upon the diagram Fig. 10 applied to the circuits connected with the plates R^3 , R^2 and R' indicate the effect upon the rear signal which the contact of the passing train with the several contact plates will have whenever the rear signal is held by the stop subject to be released by the respective circuits.

- 10 The contact plate R^4 , supposed to be located about midway of the block, will, when the circuit is completed by the train passing it, serve to energize the magnet c' by the stop of which the signal is now held at red and will release the signal, permitting it to turn to display green or caution (as shown in Fig. 3) and the signal will be held in such position by the stop of the armature of the magnet c^2 , to be again thrown into position to indicate 20 safety by the contact of the passing train with the contact plate R at the next succeeding station to the right. Soon after passing the contact plate R^4 , the train will make connection with the contact plate R^5 , connected by a wire r^5 with one of the electro magnets g^3 for operating one of the header signals E or E' , in the present instance E' , at the second signal post in advance, viz., the post A at the right hand end of the sheet. The same 30 results are repeated as the train passes each of the successive stations or posts A in its advance along the track.

Referring now to the diagram Fig. 11, the special signal posts and mechanism are denoted by A' , one being placed on the main track at each end of the shunt track. Suppose the train to be moving from left to right as before, and suppose it to be shunted onto the shunt track, after passing the signal A' at the left. As it passes onto the shunt track, it will set the rear signals at the station A' at the left as follows:—Supposing the signal at the station A to have been at white when the train passed the station, contact with the plates R^2 and R' will not affect it, but contact with the plate R^3 will set it to red. As the train passes onto the shunt track, its contact with the plates R^3 and R' will not affect the signal but its contact with the plate R^2 45 will set the signal to green in which position it will remain until the train passes from the shunt track, either by backing off from the same onto the main track or advancing along the shunt track onto the main track at the opposite end. In the former event, the signal will be left at red until the train shall have passed along the main track and successively changed it to green and then to white, as hereinbefore described and in the latter event 50 it will be finally left green until the train shall have passed the signal post at the right.

After the train has passed onto the shunt track past the contact plates R^3 , R' , R^2 , it will engage the contact plate S in circuit with 65 the line wire s leading to the magnet N or N' (see Fig. 6) of the signal post A' at the right which will advance the sprocket chain L or

L' , thereby returning the header signal which has previously been lowered, back to its upright position to permit the train coming in 70 the opposite direction on the main track to pass it without any obstructing signal. As the train passes off the shunt track, either by going forward onto the main track or by backing onto the main track, it will contact with 75 the special contact plate S' or with the contact plate S , and in either instance it will make connection through the line wire s with the magnet P or P' (see Fig. 6), thereby again setting the header to danger. After reaching 80 the main track, the order of signals will continue as before explained.

When a train is coming in a direction from the right toward the left it will engage corresponding signals on the left hand side of 85 the track, either along the main line as in diagram Fig. 10, or along the shunt track, as in Fig. 11, and the effect will be the same as that hereinabove described, a single set of signals along the track being operated by 90 trains going in either of two opposite directions, without confusion.

It is to be understood that the electricity for energizing the several magnets is to be furnished either by local batteries or, as we 95 prefer, by a battery carried by the passing train and having its poles arranged to complete circuit by having one of its poles connected with ground and the other in position to contact with the several contact plates 100 along the track.

What we claim is—

1. The railway signal system, comprising a set of rear signals fixed relatively to one another and mounted to rotate, means for operating the signals when released, header signals and means for operating them and independent electric circuits including electro magnets for releasing the signal operating mechanisms to display both the rear and the header signals, substantially as set forth. 105

2. A railway signal system, comprising a set of rear signals fixed relatively to one another and mounted to rotate, means for operating the signals when released, header signals and means for operating them and independent electric circuits including electro magnets for releasing the signal operating mechanisms to display both the rear and the header signals, the header signals being under the control of the rear signal operating mechanism to return them, substantially as 115 set forth. 120

3. In combination, rear signals, means for operating them, a header signal, means for operating it, an escapement mechanism and means for operating it, the escapement mechanism being under the control of the header signal operating means to advance it and under the control of the rear signal operating mechanism to return it, substantially as set forth. 125

4. In combination, rear signals, mechanical means for operating them, an electric circuit 130

under the control of a passing train to release the said mechanical operating mechanism, a header signal, an electric circuit under the control of an advancing train to release the 5 header signal, an escapement mechanism and means for actuating it, the said escapement mechanism being under the control of the header signal releasing circuit to permit the escapement to advance, and under the control of the rear signal mechanical operating mechanism to return it, substantially as set forth.

5. In combination, rear signals, means for operating them, electric circuits under the 15 control of a passing train to determine the signal to be displayed, an escapement mechanism and means for actuating it, the said escapement mechanism forming a part of one of the signal controlling circuits to make and 20 break the circuit according to the position of the escapement mechanism, substantially as set forth.

6. In combination, a set of signals comprising different shaped and different colored 25 arms fixed to rotate together about a common axis, signal actuating mechanism tending to move the signals whenever it is released, and different independent movable stops corresponding to the different arms of the set, under 30 the control of a passing train to arrest and release the set, substantially as set forth.

7. In combination, a set of signals fixed to rotate together, signal actuating mechanism tending to move the set whenever released, different colored spectacles under the control 35 of the signal actuating mechanism to be swung into position to correspond with the signal displayed and electric circuits adapted to be completed and broken by a passing 40 train to release the signal operating mechanism, substantially as set forth.

8. In combination, a set of rear signals, a 45 set of spectacles corresponding to the rear signals, a header signal, means for releasing it, an escapement mechanism in connection with the header signal releasing means, a

toothed disk having a common engagement with both spectacles and with the escapement mechanism, and means for operating the rear signals, substantially as set forth. 50

9. In combination, a set of rear signals, signal actuating mechanism including a sprocket chain, a header signal supported to swing into signaling position under gravity, means for releasing the signal, the sprocket chain 55 having an engagement with the projecting end of the signal to return it to its normal position, substantially as set forth.

10. In combination, a header signal, a jointed vibrating arm having an engagement with the signal to hold and release it, a swinging gravity stop under the control of the signal to regulate the movements of the jointed vibrating arm, and means for operating the vibrating arm as a whole and independent 65 means for operating one of its joints, substantially as set forth.

11. In combination, a main track, a shunt track, a header signal under the control of a train passing along the main track, an electric circuit including electro magnets for operating the header signal and under the control of a train on the shunt track, contact pieces in position to be electrically connected and disconnected by the movement of the 75 signal, the said electro magnets in the operating circuit having one pole of each connected with a single line wire and the opposite pole of each connected the one with one contact piece and the other with the other 80 contact piece, substantially as set forth.

12. In combination, a rear signal and its operating mechanism, a header signal under the control of the rear signal operating mechanism to return it, and independent mechanism for releasing and returning the said header signal, substantially as set forth. 85
